UNITED STATES PATENT OFFICE.

ARTHUR MIDDLETON ROSE, OF YONKERS, NEW YORK, ASSIGNOR TO THE
W. & J. SLOANE, OF NEW YORK.

DESIGN FOR CARPET.

SPECIFICATION forming part of Design No. 25,234, dated March 3, 1896.

Application filed January 31, 1896. Serial No. 577,632. Term of patent 3½ years.

To all whom it may concern:

Be it known that I, ARTHUR MIDDLETON ROSE, a citizen of the United States, and a resident of Yonkers, in the county of Westchester and State of New York, have invented a new and original Design for Carpets and Borders, of which the following is a specification.

This invention is composed of two parts—namely, the design A for a carpet and the design B for a border; and I do hereby declare that the drawing accompanying this specification conveys to any one a clear understanding of the same and is sufficient to enable such person to use my invention.

The design A is characterized by curving and spiral stem forms, interspersed with small bunches of flowers and by a central irregular figure having a pendent chain.

The border B is characterized by conven-

tional spiral forms with pendent chains of buds, interspersed ferns and strings of flowers and leaves.

What I claim as new, and desire to secure by Letters Patent, is—

1. In a design for carpet, the body A substantially as shown.
2. In a design for carpet, the border B, substantially as shown.
3. The design for carpet comprising the body A and the border B, substantially as shown.

In testimony whereof I have signed my name to this specification in the presence of two subscribing witnesses.

ARTHUR MIDDLETON ROSE.
